Primary Examiner — Cynthia Ramirez(74) *Attorney, Agent, or Firm* — Michael A. Blake(57) **CLAIM**

The ornamental design for a debris barrel, as shown and described.

DESCRIPTION

FIG. 1 is a perspective view of a debris barrel showing my new design;

FIG. 2 is a front view of the debris barrel;

FIG. 3 is a rear view of the debris barrel;

FIG. 4 is a left side view of the debris barrel;

FIG. 5 is a right side view of the debris barrel;

FIG. 6 is a top view of the debris barrel;

FIG. 7 is a bottom view of the debris barrel; and,

FIG. 8 is an exploded view thereof.

In FIG. 7, the broken lines depict portions of the debris barrel that form no part of the claimed design.
